(57) **CLAIM**

The ornamental design for a display device, as shown.

DESCRIPTION

FIG. 1 is a front, top, and right-side perspective view of a display device that has the design. Apart from the text, the front, top, and right-side view is a mirror image of this view. FIG. 2 is a front elevation view of the display; and,

FIG. 3 is a bottom plan view of the display.

The particular wording and numbers seen in the drawings is for illustrative purposes only, and forms no part of the claimed design.
